UNITED STATES PATENT OFFICE

ALLISON J. THOMPSON, OF CLEVELAND, OHIO

CONNECTION FOR LAMP HANGER CONTACTORS

Application filed July 10, 1930. Serial No. 466,919.

My invention relates to improvements in connectors for lamp hanger contact assemblies and, particularly, to connectors for lamp hanger contact assemblies comprising an upper stationary hanger structure adapted to be mounted at an elevated point and a lower lamp carrying hanger structure adaptable for releasing latching engagement therewith.

The present invention has particular relation to an improved connector for contact assemblies such as shown and described in my co-pending application Serial No. 380,888, filed July 25, 1929, to which reference may be had if desired.

The general object of the present invention is to provide an improved connector for lamp hanger contactors of the above type of such nature that, while embodying a minimum number of relatively rugged parts, it provides a means for protecting the connection from the elements, particularly water, corrosion, dust, or the like irrespective of where the lamp hanger structure is exposed. It further contemplates the provision of a connector wherein means are provided for preventing short circuiting of the electrical current therethrough to parts other than the lamp and, at the same time, provides a means for protecting the connector that is easily removable when it is desired to have access thereto.

Further objects of the invention will be in part obvious and in part will appear more in detail hereinafter.

In the drawing, Fig. 1 is a sectional view showing a contactor structure embodying the features disclosed in my invention; Fig. 2 is an elevational view of the contactor structure; and Fig. 3 is a sectional view taken on the line 3—3 of Fig. 1.

Referring to the drawing, I have shown the part of a lamp hanger structure comprising a contactor supporting arm 1 that is adapted to partly if not wholly surround an insulator body portion 2 and hold such body portion in the proper position. As shown in Figs. 1 and 2, the insulator body portion 2 is provided with a depending annular lip or flange 2' on its lower end, this lip or flange serving to

direct water away from the connection hereinafter described and to prevent leakage past the protecting parts for the connection that might take place due to capillary attraction.

The insulator body portion 2 has a metallic contact member 3 mounted on the top thereof and held thereon by a screw bolt 4 passing downwardly through the insulator body portion, and this metallic contact member fits within a depending bell shaped metallic contact member 5 carried by the upper part of the lamp hanger structure. It will be understood that the metallic contact member 3 is preferably movable vertically with relation to the metallic contact member 5 and into and out of operative engagement therewith.

The lower end of the screw bolt 4 provides a means for operatively connecting one end of a current conducting wire 6 to the contactor structure, electrical current passing through the current contactor members 5 and 3, screw bolt 4, and current conducting wire 6 to the lamp (not shown). Such current conducting wire is operatively connected to the lowermost end of the screw bolt 4 by means of a nut 7 which bears against the under side of the lowermost one of a pair of washers 8 between which the end of the current conducting wire is disposed. The upper washer 8 bears against the inner surface of an annular externally threaded member 9 having a square shank 10 adapted to fit within a substantially square opening or socket 11 in the lowermost end of the insulator body portion. As shown in Figs. 1 and 2, a cap member 12, which is internally threaded adjacent its uppermost end is adapted to cooperate with the externally threaded annular member 9 and surround the connection hereinbefore described between the current conducting wire 6 and the screw bolt 4. The lowermost end of the member 12 is provided with an opening 13 through which the current conducting wire 6 is adapted to pass.

With this construction, the cap member 12 may be placed upon the current conducting wire 6 by passing the free end of the wire through the opening 13 and such cap may be

moved downwardly on the current conducting wire to such position as to permit free access to the end of the screw bolt 4, whereby the free end of the current conducting wire 5 may be operatively connected to such screw bolt. Then, the cap member 12 may be moved upwardly on said wire until it is brought into engagement with the annular member 9 whereupon it may be rigidly secured thereto by the cooperating internal and external threads on the cap member 12 and the annular member 9.

Referring to the drawing and the preceding description, it will be seen that I have 15 provided a connector for a lamp hanger contactor structure of such nature that the connection between the current conducting wire and the contactor structure will be protected at all times against both effects of the elements, dust or the like, and, at the same time, have provided a device wherein such protection may be easily removed to permit access 20 to be had to the connection between the current conducting wire and the contactor structure.

What I claim is:

1. A connector for a lamp hanger contact assembly comprising an insulator body portion, a supporting means therefor, current 25 conducting means extending through said insulator body portion for connection with a current conducting line, a connection protecting means including a cap member for covering the connection between said current conducting member and the current conducting line, means for connecting said cap member and said insulator body portion, and an annular depending lip on said insulator body portion surrounding the connection between said cap member and said insulator body portion to cut off leakage by capillary attraction 30 past said point of connection.

2. A connector for a lamp hanger contact assembly comprising an insulator body portion, a supporting means therefor, current 35 conducting means extending through said insulator body portion for connection with a current conducting line, a connection protecting means including a cap member for covering the connection between said current conducting member and the current conducting line, means for connecting said cap member and said insulator body portion including a socket in said insulator body portion 40 and a member adapted to interfit with said socket having means thereon for connecting said member and said cap member, and a depending lip on said insulator body portion surrounding the connection between said member adapted to interfit with said socket 45 and said cap member to cut off leakage by capillary attraction past said connecting point.

3. A connector for a lamp hanger contact 50 assembly comprising an insulator body por-

tion, a supporting means therefor, a contact member secured to one end of said insulator body portion, current conducting means having connection with said contact member and extending through said insulator body portion with a part thereof extending beyond said insulator body portion for connection with a current conducting line, a connection protecting means including a cap member for covering the connection between said current 70 conducting member and the current conducting line, means for connecting said cap member and said insulator body portion, and a depending lip on said insulator body portion surrounding the connection between said cap member and said insulator body portion to cut off leakage by capillary attraction past 75 said connecting point.

In testimony whereof I hereby affix my signature.

ALLISON J. THOMPSON.
